United States Patent Office

Des. 214,664
Patented July 15, 1969

214,664

EGG CARTON

Bryant Edwards, Clarendon Hills, Ill., assignor to Illinois
Tool Works Inc., Chicago, Ill., a corporation of
Delaware

Filed Feb. 19, 1968, Ser. No. 10,627

Term of patent 14 years

Int. Cl. D9—04

U.S. Cl. D9—190

Fig. 3

Fig. 4

Fig. 5

Fig. 6

Fig. 7

Fig. 8

FIG. 1 is a perspective view of an egg carton showing my new design;

FIG. 2 is a partial top plan view thereof of the left portion of FIG. 1;

FIG. 3 is a partial top plan view thereof of the right portion of FIG. 1 wherein the bottom of the egg pocket comprises several concentric rings;

FIG. 4 is a side elevational view of the egg carton shown in FIG. 1;

FIG. 5 is an end elevational view of the egg carton shown in FIG. 1;

FIG. 6 is a fragmentary sectional view of the egg carton shown in FIG. 2 as viewed along lines 6—6 thereof;

FIG. 7 is a fragmentary sectional view of the egg carton shown in FIG. 3 as viewed along lines 7—7 thereof; and

FIG. 8 is an end sectional view of the egg carton shown in FIG. 2 and viewed along lines 8—8 thereof.

I claim:

The ornamental design for an egg carton, as shown and described.
